FLOOR LAMP

Motoko Ishii, Tokyo, Japan, assignor to Yamagiwa
Electric Company Ltd., Tokyo, Japan

Filed Apr. 13, 1971, Ser. No. 133,771

Term of patent 14 years

Int. Cl. D26—05

U.S. Cl. D48—20 A

FIG. 3.

FIG. 4

FIG. 1 is a front view of the floor lamp showing my new design according to the invention;

FIG. 2 is a top plan view thereof;

FIG. 3 is a side view thereof; and

FIG. 4 is an enlarged fragmentary view thereof, the floor lamp being fragmentarily shown for convenience of illustration and purposes of disclosure.

I claim:

The ornamental design for a floor lamp, as shown and described.
